United States Patent Office

Des. 181,729
Patented Dec. 17, 1957

181,729

CHAIR

James E. Jones and Edward P. Stevens, Toledo, Ohio,
assignors to The Hettrick Manufacturing Company,
Toledo, Ohio, a corporation of Ohio

Application December 27, 1955, Serial No. 39,486

Term of patent 14 years

(Cl. D15—1)

Fig. 1.

Fig. 2.

FIG. 3.

Figure 1 is a front perspective view of the chair showing our new design;

Figure 2 is a rear elevation of the chair; and

Figure 3 is a side elevation on an enlarged scale of the chair. The broken lines denote a section of indeterminate length.

We claim:

The ornamental design for a chair, as shown and described.
